(Cl. D87—3)

To all whom it may concern:

Be it known that I, Vincent Maiorana, a citizen of the United States of America, residing in Laurelton, county of Queens, and State of New York, have invented a new, original, and ornamental Design for a Moneybag or Similar Article, of which the following is a specification, reference being had to the accompanying drawing, forming part thereof, wherein,

I claim:

The ornamental design for a moneybag or similar article, substantially as shown.

VINCENT MAIORANA.
